CLAIM

The ornamental design for an articulatable parking space barrier, as shown and described.

DESCRIPTION

FIG. 1 is a perspective view of an articulatable parking space barrier showing my new design, the padlock being shown in broken lines for illustrative purposes only;

FIG. 2 is a top view thereof;

FIG. 3 is a bottom view thereof;

FIG. 4 is a front view thereof;

FIG. 5 is a right side view thereof;

FIG. 6 is a rear view thereof;

FIG. 7 is a left side view thereof;

FIG. 8 is a perspective view showing the articulatable parking space barrier in the down position; and

FIG. 9 is an elevational view of the barrier in the down position on an enlarged scale.
